JOHN WILLIAM SMITH, OF SYRACUSE, NEW YORK.

MIXING DEVICE.

Application filed July 13, 1927. Serial No. 205,347.

The present improvements while adapted for being used in the admixturing of various gases with each other and various liquids with each other, and also one or more gases with one or more liquids, are herein illustrated as being especially arranged and adapted for use in charging air with liquid fuel, usually in spray form, and bringing the said fuel to a highly comminuted condition and also 10 intimately interassociating the said comminuted fuel with and uniformly throughout the air.

A leading object of the present improvements is to provide fuel-charged-air of the 15 highly conditioned character described, for economically operating furnaces as, for instance, the manufacture or working of steel or other metals and for operating oil or gas engines most advantageously. A further object is to provide an efficient system and an 20 arrangement of apparatus for mixing or blending two or more gases or two or more liquids as required for practically attaining maximum efficiencies and economies when employed in various industries.

In this connection it will be remembered that serious losses of fuel are incurred through the common practice of using air in excessive quantities and thereby reducing the 25 intensity and completeness of combustion; besides occupying valuable space and carrying off much heat and thus resulting in an unnecessary waste of fuel.

For accomplishing the said results, the 30 apparatus hereinafter described is shown as being organized and equipped for subjecting a stream of the charged air while forwardly-flowing in a conduit, to a progressive conditioning treatment involving a complex of actions and forces whereby the stream is repeatedly diverted, reformed and reversely shifted and intermixed during its flowage, while any of the uncommunited or heavier bodies, as globules or vesicles, are subjected 35 to a repeated and forcible impactive, disintegrative and dispersive treatment whereby effectively to interassociate all of the materials comprised in the forwardly flowing stream.

One of the leading features of the present invention, as hereinafter more fully explained in connection with the accompanying illustrations, consists in an extension of the 40 transversely curved columnar formation set forth in my co-pending application, Serial No. 200,309 filed June 21, 1927, a complete an-

nular construction, and in the combinations with the annular conduit channel thus obtained, of two series of stream-treating annuli appertaining, respectively, one series to 45 the transversely-concave channel-wall, and having, respectively, their stream-guiding and dividing blade-portions positioned on different angles relatively to the wall-surfaces and relatively to the flowage-path of the 50 stream; and, also thereby forming (intermediate to successive said annuli) merging-chambers having, in an axial plane of conduit, successively reversed positions and specific 55 modes and ranges of action.

A further feature resulting from, or produced by, the above described annular system of organization, is the construction of the 60 said blade-portions of the annuli, or of certain of them, to have an inclined form, or position, laterally thereof, and thereby adapt them to impart to the material flowing therethrough, a lateral trend or movement which 65 may be reversed in successive chambers respectively, and may extend throughout the 70 circuit of the chamber or chambers so provided, and thus effect a shifting rotatively of and in the channel of successive merging masses in one direction and of other successive said 75 masses in an opposite direction and thereby 80 increase the aggregate effect.

These and other features, capabilities and advantages of the invention, will appear from the subjoined detail description of specific 85 embodiments thereof, illustrated in the accompanying drawings in which

Figure 1 is a longitudinal section of a complete mixing device constructed according to one embodiment of the present invention;

Figs. 2 and 3 are fragmental sections showing different types of interceptors;

Fig. 4 is a fragmental section illustrating a type of conduit which can be used with the embodiment illustrated in Fig. 1 in which the interceptors are integral with the main 100 walls of the conduit;

Fig. 5 is a transverse section on the line 5-5 of Fig. 1 looking upwardly;

Fig. 6 is a transverse section of the embodiment illustrated in Fig. 1 showing one row 105 of interceptor blades diagrammatically;

Fig. 7 is a transverse section similar to Fig. 6 showing a single row of outer and inner interceptor blades diagrammatically;

Fig. 8 is a transverse section similar to Fig. 110 6 showing diagrammatically a single row of outer and inner interceptor blades of another

type in which the left hand area shows the outer row overlapping the inner row and the right hand area shows the inner row overlapping the outer row;

5 Fig. 9 shows a fragmental longitudinal section of the interceptor blade construction illustrated in Fig. 1;

10 Fig. 10 is a fragmental longitudinal section similar to Fig. 9 showing successive rows of interceptor blades diagrammatically;

15 Fig. 11 is a longitudinal section similar to Fig. 1 of another embodiment showing a different type of interceptor blades and showing them integral with the main walls;

20 Fig. 12 is a transverse section of the embodiment illustrated in Fig. 11 but showing diagrammatically various types of interceptor blades, the lower left quarter showing a single row of inner blades; the upper left quarter showing a single row of outer blades and a single row of another type of inner blades in their respective positions relative to one another; the upper right quarter showing a single row of outer blades similar to those shown in the upper left quarter but with a single row of inner blades having curved edges; and the lower right quarter showing a single row of inner blades similar to those shown in the upper right quarter and 30 a single row of outer blades also having curved edges;

Fig. 13 is a fragmental transverse section showing certain of the forces of the stream diagrammatically;

35 Figs. 14, 15 and 16 show still further types of interceptor blades which can be used with the present mixing device;

40 Figs. 17 and 18 show diagrammatically a row of inner and outer blades respectively of the type used in the embodiment of Fig. 1;

45 Figs. 19 and 20 show diagrammatically another arrangement of the interceptor blades which can be used with the present mixing device.

50 For convenience of illustration and description, the several conduit columns have been illustrated in the drawings as being located in vertical positions; in practice, however, any one of these conduits may be arranged for being used not only in a vertical position, but may also be adapted and readily connected for being used in a horizontal or inclined position, whenever such a change may be found necessary or more desirable.

55 In any such instance, the conduit column may be provided with, or be used in connection with some suitable supporting means or devices, such as are well known and commonly employed for many analogous purposes in

60 various industrial and other establishments; for these reasons it has been deemed to be unnecessary to herein more fully describe the said variations in the positioning of the conduit column. In this connection it is to be noted that the conduit columns may any of

them be made of such sizes, both as to length and cross-sectional dimensions as shall be suitable for the service and capacity found to be needful in any particular instance. Therefore, in practice, the conduit column and the 70 details and accessories thereof and therefor may be of small dimensions when the apparatus is constructed for work requiring the treatment of only small volumes, and may be of large dimensions when employed for treating large volumes of the materials, as for instance, when proportioned for admixing large volumes of gases, or for blending large quantities of liquids.

75 In the embodiment illustrated in Fig. 1, there are shown two supports 1 and 2 which receive the annular flange 3 of the intake member 4 which consists of an inwardly flaring downwardly extending cone-shaped wall 5 terminating in a lower tubular portion 6 80 having a flange 7 secured to the flange 8 of the air intake conduit 9. Extending into the conduit 9, there is provided the fuel supply nozzle 10, the mouth of which is positioned to direct its charge centrally of the air stream 85 passage 11 of the conduit 9.

90 On the intake member 4 and extending upwardly therefrom, there are preferably formed four arms 12 which support the cap 13 which has a cone-shaped member 14, the peak of which aligns substantially with the center of the passage 15. The cap 13 extends upwardly and forms an annular support 16 for the inner tube member B which forms the inner wall of the mixing conduit. The 95 flange 3 of the intake member 4 receives the annular flange 17 of the outer tube member F which forms the outer wall of the mixing conduit. In the present instance, the outer tube member F consists of two tubular members 18 and 19 connected to one another in the usual way, the upper tubular member 19 having an annular flange 20 at its upper end to receive the annular flange 21 of the outlet member 22, having a passage 23 leading 100 to the combustion chamber in the usual way.

105 In the present instance, the cap 13 properly centers the lower end of the inner tubular member B. The upper end of the tubular member B is preferably provided with a cap 115 24 to close its upper end. A spider 25, preferably having three legs 26, has its annular portion 27 engage the cap 24 and the extremities of its legs 26 engage the inner periphery of the lower end of the outlet member 22 properly to center the upper end of the inner tubular member B relative to the outer tubular member F.

110 The annular surface 16 of the cap 13 extends beyond the outer periphery of the tubular member B to form an annular seat for the inner interceptor members now to be described. The lower edge of the flange 28 of the cap 24 forms a shoulder on the outer periphery of the member B and functions to 115 120 125 130

engage the uppermost inner interceptor member to anchor the inner interceptor members against displacement.

The inner interceptor members, in the present instance, consist of a plurality of sleeves having upward outwardly flaring interceptor blades 29. The lowermost sleeve 30, in the present instance, is comparatively short in length and has its interceptor blade extending upwardly and outwardly from the upper end thereof at an angle of about sixty degrees to the tubular member B. The next lowermost sleeve 31, similar to the sleeve 30, intimately engages the tubular member B, and being positioned thereby has its lower edge inclined to conform to the upper face of the lowermost interceptor blade 29. Above the sleeve 30, in the present instance, there are provided three sleeves 31 in alignment with one another. Above the uppermost sleeve 31, there is provided a sleeve 32, the lower edge of which is inclined to conform to the upper surface of the interceptor blade 29 of the uppermost sleeve 31, and the upper edge of which forms a seat for the lower edge of the flange 28.

The interceptor blades 29, as diagrammatically shown in Fig. 6, consist of an annular row of teeth 33, the edges of which converge in points 34 terminating beyond the middle of the annular chamber C.

Adajacent to the inner periphery of the tubular member F, there are provided a plurality of interceptor members, the lowermost interceptor member, in the present instance, consisting of a sleeve portion 35 fitting snugly against the inner peripheral wall of the tubular member F, and having a lower interceptor blade 36 extending inwardly and flaring upwardly from the lower end thereof, and an upper interceptor blade 37 extending inwardly and flaring upwardly from the upper end thereof. The lower annular edge of the sleeve 35 rests on the shoulder formed by the intake member 4 adjacent to its flange 3. Above the sleeve 35, in the present instance, there are provided three other outer interceptor members of similar construction and in alignment with one another, each consisting of a sleeve portion 38 fitting snugly against the inner peripheral wall of the tubular member F and having its lower edge inclined to conform with the adjacent interceptor blade and resting thereon, and having an interceptor blade portion 39 extending inwardly and flaring upwardly. The blade portions 36, 37 and 39, in the present instance, form an angle of approximately forty-five degrees with the peripheral wall of the tubular member F. Above the uppermost sleeve 38, there is formed a short sleeve 40, the lower edge of which conforms to the upper surface of the uppermost blade portion 39, and the upper edge of which conforms to the lower projecting portion of the flange 21,

so that the outer interceptors are securely anchored in place between the intake member 4, flange 21 and tubular member F.

In Fig. 9, by means of the lower broken edges, the arrangement of nesting the several elements is clearly illustrated.

Each of the interceptor blades 36, 37 and 39, consist of an annular row of teeth 41 diagrammatically shown in Fig. 7 as having edges that converge in points 42 that extend beyond the middle of the annular chamber C toward the tubular member B. The teeth 33 and 41 are so positioned relative to one another that each tooth 41 extends into the adjacent opposite space between two adjacent opposite teeth 33.

In Figs. 8 and 10, the inner interceptor blades are illustrated as having the space between adjacent teeth starting a distance removed from the tubular wall member B, whereby the lateral converging edges lose in length but the stream deflecting surfaces are increased. It will be noticed by an examination of Fig. 10 that the stream flowing upwardly with respect to the construction there illustrated will engage the concave surfaces of the outer teeth 41 and the convex surfaces of the inner teeth 43.

In Fig. 13, there is illustrated one of the important results secured, in practice, by the construction of the stream-channel, (or conduit-channel), with the said walls thereof in the described transversely-curved form, and also symmetrically positioned, these walls, preferably, having a longitudinal parallelism. Thus said walls, or the inner surfaces, as *f* and *b* thereof, are oppositely disposed, the outer wall F having the said concave inner surface *f*, and the inner wall B having the convex outer surface *b*. The stream while flowing through said channel, has the materials and the body thereof alternately treated in a dispersive and interblending manner and is forced first toward one said wall and then toward the other said wall, thereby creating certain flowage-lines, with resultant or force-lines having, or tending to develop a peculiar spreading and lateral action of a dynamic nature.

For instance, a flowage-line, or force, leading from a point 50 on the concave surface *f*, and directed and spreading to or toward the points 51, 52, on said convex surface B, will naturally react (on equal but reverse angles) toward the widely separated points 53, 54, respectively, on said concave surface *f*. Thus, any such dynamic action, or flowage lines as 55, 56, react on more widely spreading lines as 57, 58, toward a greater arc or zone on the said concave surface; also, although not here shown, it will be evident that said reactionary effect may be shifted or directed to a more advanced position or height longitudinally of the channel by reason of the stream flowing therein.

When said conduit surfaces *f* and *b* are extended to an annular form, the above described operation of said flowage-reaction and force-lines, which may occur simultaneously at several points in the circuits, operate throughout the entire circumference, and thereby tend to aid in a progressive manner to the diffusion and intermixing of the stream-elements during the flowage of these elements lengthwise of the conduit with the described stream-shifting effects.

Also, in Fig. 13, force-lines are shown extending from point 59 on the convex wall to points 60, 61, respectively, on said concave wall *f*, and there reacting by lines 62, 63, to the short arc on the convex-wall face *b*. Thus the reaction flowage forces leading from the convex wall tend to return thereto with only a slight, if any, spreading effect.

In the construction of these conduits, it is desirable to use the incisor type of interceptors heretofore described. With these types of blades, see Fig. 4, a varying pressure will be created in the stream during its passage from one blade to another. The line 66 in Fig. 4 indicates diagrammatically the rise and fall of the pressure in the stream portions during their upward movement, the bulges 67 below the interceptors 29, 39, indicating the increase in pressure in the stream portions as distinguished from the decrease in pressure beyond the interceptor members 29, 39. From the foregoing it will thus be seen that in the present device the interceptors not only serve constantly to divide and subdivide the stream into a plurality of stream portions, but due to the arcuate cross section of the stream channel, see Fig. 13, cause a pulsating rise and fall in pressure of the stream portions as they are directed from one wall *b* to the other wall *f* and back again, and similarly cause a different rise and fall in the stream portions as they approach an interceptor and again leave the same.

It will further be seen that in addition to this variation in pressure from side to side and longitudinally of the conduit, the concave lower surfaces of the teeth 41 and the convex lower surfaces of the teeth 43 will serve to impart a constantly varying change of speed in the mixture. In other words, while the area adjacent the tubular member *B* is smaller relative to the area adjacent to the tubular member *F*, whereby the stream portions when being deflected from the larger area adjacent to the tubular member *F* into the smaller area adjacent to the tubular member *B* resulting in a constantly alternating expansion and contraction of the stream, the convex lower surfaces of the blades 43 will permit the stream portions when passing the same more quickly to cross the same than the concave lower surfaces of the blades 41 which will function to cause the stream portions to crowd together on the

blade rather than to spread apart and leave the blade.

In this connection, it will be remembered that a well known phenomenon in the flowing of gases and liquids through conduits therefor, is the formation of a smaller and more rapid stream flowing through the slower moving mass of the main stream. This unequal rate of flowage may readily occur in conduits of various sizes, lengths and proportions, and especially when the conduit (as a chimney, pipe or flue) has a cross-sectional form of small dimension in one direction and in a direction transverse thereto has a much larger dimension. The latter condition appertains to the form of annular channel herein illustrated, as will be evident from the drawings. For instance in Fig. 6, the thickness of the channel is indicated by the short radial line *r*, whereas the transverse length of the channel, measured in a circle midway between the wall-faces *F* and *B*, is fully six times as great as the length of said radial *r*. Thus, in practice, it becomes possible (especially in view of well-known instances of the class above noted) for the up-flowing stream to have on one side of the annular conduit, a different rate of flowage, and also a different character of admixture, than on the opposite side thereof.

These results are overcome, or prevented, in the present annular system by the use of a construction and organization of the stream-treating blades of the annuli (or of a sufficient number of them) whereby the blades have transversely thereof an inclined position, the angle or pitch and the proportions thereof being sufficient for imparting to the material up-flowing against and between them, a trend and flowage movement circumferentially within the conduit channel. By arranging said inclines in opposite directions in successive merging-chambers, respectively, said circumferential flowage may be, for instance, toward the right hand and continuous in each alternate chamber of one series, and toward the left hand and continuous in each intervening said chamber; and while these flowages are continuing rotatively of the column, the upflow of the stream is also continuously supplying material into each of the chambers, and also, in equal quantity, taking material out of those chambers, so that any given mass of material starting upward in the stream will be repeatedly flowed back and forth circumferentially of and in the channel and so be repeatedly merged with, and inter-associated with other material or mass components of the stream. Furthermore, as will now be evident, the said treatment of the material by the described rotative flowages in reverse directions alternately, is now accomplished in a manner which avoids any rotation of the stream as a whole, and thus avoids the creation therein of any objectionable cen-

trifugal action or any segregative effect arising therefrom.

In other words, as diagrammatically illustrated in Figs. 19 and 20, the blades *a* of each 5 interceptor for instance are staggered relative to one another so that the stream in passing upward through the conduit, illustrated in Fig. 1, will not only be deflected from the wall *B* to the wall *F* and back again, but also be 10 directed in a spiral direction. In this case, the opposing blades *x*, see Fig. 20, when in operative relation to the blades *a* will be inclined in the opposite direction thereby to cause the stream portions as they are received by the 15 blades *x* to be shifted in the opposite direction to that caused by the inclination of the blades *a*, and thus again a further rise and fall in pressure will be created in the stream portions passing from one interceptor 39 to 20 the succeeding interceptor 29 and so on, and in addition there will be positively prevented the formation of any independent uneffected streams or parts.

For different conditions the teeth 29 and 39 25 of the embodiment illustrated in Fig. 1 may assume different widths and forms without departing from the general spirit of the invention. As an instance, in the embodiment illustrated in Fig. 2, the outer sleeves 38 are 30 constructed similar to those illustrated in Fig. 1 having similarly inclined teeth 39, the inner sleeves 31', however, having upwardly curved teeth 29' instead of the plane teeth 29 of the construction illustrated in Fig. 1. And, 35 in the embodiment illustrated in Fig. 3, the teeth 29' and 39' of both the inner sleeves 31' and the outer sleeves 40' respectively are curved.

In the embodiment illustrated in Fig. 11, 40 there is provided an intake member 68 having an annular channel 69, an inlet passage 70 and a recess 71. The intake member is provided with a flange 72 around its inlet passage 70 to receive the flange 73 of the air supply tube 74. The air supply tube 74 is preferably provided with a fuel supply nozzle 75 which extends centrally into the passage 70, as shown. The recess 71 is formed to serve as a seat and securely to anchor the lower end of 45 the inner tubular member *B* against displacement. The intake member is also provided with an annular flange 76 adjacent to its annular chamber 69 to receive the annular flange 77 at the lower end of the outer tubular member *F*. The outer tubular member *F*, as shown 50 in Fig. 12, is preferably composed of two sections 78 and 79 provided with longitudinally extending flanges 80, 81, and 82, 83, respectively, secured to one another as shown. 55 The upper end of the tubular member *B* is preferably provided with a cap 84 to close the same, and in addition thereto the upper end of the member *B* has secured thereto the spider 60 consisting of the annular member 86 engaging the tubular member *B* adjacent to the

lower edge of the cap 84 and the arms 87, the extremities of which engage the lower periphery of the outlet member 88 thereby properly to center the member *B* relative to the member *F*. The member 88, as shown, is provided with an annular flange 89 to engage and be secured to the annular flange 90 of the tubular member *F*. 70

In this embodiment, the interceptor members are illustrated as integral with the main 75 wall members *B* and *F*. The interceptor members 91 of the tubular member *B* extend at right angles to the axis of the member *B*. The member *F* is provided with two different types of interceptor blades, one type, 80 the blades 92, which extend downwardly and inwardly, and the other type, the blades 93, which extend upwardly and inwardly. In the embodiment illustrated, each row of blades 91 extends between a row of downwardly extending blades 92 and a row of upwardly extending blades 93. 85

In the embodiment illustrated in Fig. 12, different formations of teeth are illustrated, the lower left quarter 94 showing a row of 90 inner teeth 95 which extend from the tubular member *B* entirely across to the tubular member *F* so that the converging points 96 of the teeth 95 practically engage the tubular member *F*. In the zone 97, the upper left 95 quarter, there are shown a row of inner blades 98 and a row of outer blades 99 similar to those illustrated in Fig. 8.

In the upper right quarter 100, there are shown a row of outer blades 101 similar to 100 the blades 99 shown in the upper left quarter, and a row of inner blades 102 having curved edges.

In the lower right quarter 103, there are shown a row of inner blades 104 similar to 105 the blades 102 of the upper right quarter, and a row of outer blades 105 having curved edges.

In Figs. 14, 15 and 16, still other combinations of blades are shown. In Fig. 14, 110 the line 106 designates the zone of one combination having a downwardly inclining blade 107, and an upwardly inclining blade 108 extending from the wall *F*, and two horizontally extending blades 109 and 110 extending from the wall *B*, the blade 109 extending above the blade 107 and the blade 110 extending above the blade 108. 115

The line 111 designates a zone containing another combination of blades in which there 120 is shown an upwardly inclining blade 112 and a downwardly inclining blade 113 extending from the wall *B*, and three horizontally extending blades 114, 115 and 116, extending from the wall *F*, the blade 112 125 extending between the blades 114 and 115, and the blade 113 extending between the blades 115 and 116.

The line 117 designates a zone containing 130 still another combination of blades in which

there is shown a horizontally extending blade 118, an upwardly inclining blade 119 and a downwardly inclining blade 120 extending from the wall B, and two horizontally extending blades 121 and 122 extending from the wall F, the blade 121 extending between the blades 119 and 120, and the blade 122 extending into the pocket formed above the blade 120.

10 In Fig. 15, still another combination of blades is shown, the tubular member B having extending therefrom the upwardly curved blade 123, the downwardly curved blade 124, the upwardly curved blade 125, the downwardly curved blade 126, and the upwardly curved blade 127, while the outer tubular member F has formed thereon the horizontally extending blades 128 and 129, the blade 128 extending into the pocket formed beneath the blade 123 and the blade 129 extending between the blades 123 and 124. On the member F there are also formed the upwardly curved blade 130, the upwardly inclined blade 131, and the upwardly curved blade 132, the upwardly curved blade 130 extending between the blades 124 and 125, the upwardly inclined blade 131 extending between the blades 125 and 126, and the upwardly curved blade 132 extending 30 between the blades 126 and 127.

In Fig. 16, still another combination of blades is shown, the simplest type, in which the blades 133, 134, 135 and 136 all extend vertically to the axis of the tubular members 35 B and F, the blade 135 extending between the blades 133 and 134, and the blade 134 extending between the blades 135 and 136.

In Figs. 17 and 18 there are shown plan views of the blades illustrated in Fig. 16.

40 From the foregoing it will be seen that various changes and modifications may be made to the details of construction without departing from the general spirit of the invention as set forth in the appended claims.

45 I claim:

1. In a device of the character described, the combination with a conduit having an annular inner wall, of an annular outer wall forming an annular channel with said inner wall, a plurality of interceptors extending from the outer wall across the middle of the conduit forming passage toward the inner wall, and a plurality of interceptors extending from the inner wall across the middle of the conduit forming passage toward the outer wall and into the chambers formed between the interceptors extending from said outer wall whereby the stream directed through said conduit will be directed from one opposing wall to the other, said interceptors being each composed of a series of blades having edges converging to points terminating beyond the middle of the channel formed between said walls.

65 2. In a device of the character described,

the combination with a conduit having an annular inner wall, of an annular outer wall forming an annular channel with said inner wall, a plurality of interceptors extending from the outer wall across the middle of the conduit forming passage toward the inner wall, and a plurality of interceptors extending from the inner wall across the middle of the conduit forming passage toward the outer wall and into the chambers formed between the interceptors extending from said outer wall whereby the stream directed through said conduit will be directed from one opposing wall to the other, said interceptors being each composed of a series of blades having edges converging to points terminating beyond the middle of the channel formed between said walls, the points of the interceptor blades extending from the outer wall being grouped closer to one another than the points of the interceptor blades extending from the inner wall thereby to increase the resistance to the stream portions when adjacent said inner wall and further to increase the pressure in said stream portions when adjacent said inner wall.

3. In a device of the character described, the combination with a conduit having an annular inner wall, of an annular outer wall forming an annular channel with said inner wall, a plurality of interceptors extending from the outer wall across the middle of the conduit forming passage toward the inner wall, and a plurality of interceptors extending from the inner wall across the middle of the conduit forming passage toward the outer wall and into the chambers formed between the interceptors extending from said outer wall whereby the stream directed through said conduit will be directed from one opposing wall to the other, said interceptors being each composed of a series of blades having edges converging to points terminating beyond the middle of the channel formed between said walls, the blades of alternate interceptors being inclined in opposite directions to impart to the stream an alternately opposite spiral movement.

4. In a device of the character described, the combination with a conduit having an annular inner wall, of an annular outer wall forming an annular channel with said inner wall, a plurality of interceptors extending from the outer wall across the middle of the conduit forming passage toward the inner wall, a plurality of interceptors extending from the inner wall across the middle of the conduit forming passage toward the outer wall and into the chambers formed between the interceptors extending from said outer wall whereby the stream directed through said conduit will be directed from one opposing wall to the other, said interceptors being each composed of a series of blades having edges converging to points terminating be-

yond the middle of the channel formed between said walls, the points of the interceptor blades extending from the outer wall being grouped closer to one another than the 5 points of the interceptor blades extending from the inner wall thereby to increase the resistance to the stream portions when adjacent said inner wall and further to increase the pressure in said stream portions when adjacent 10 said inner wall, and the blades extending from the inner wall forming a greater angle with the inner wall than the angle formed with the outer wall by the outer blades.

15 5. In a device of the character described, the combination with a conduit having an inner annular wall forming a tube, of an outer annular wall, caps for closing the ends of the tube formed by the inner wall, a discharge 20 conduit in communication with the discharge end of the annular channel formed between said inner and outer walls, an intake conduit in communication with the intake end of said channel, a plurality of rows of interceptors 25 extending from the inner wall across the middle of said channel and inclining toward the discharge end and toward the outer wall, and a plurality of rows of interceptors extending from the outer wall across the middle of said 30 channel and inclining toward the discharge

end and toward the inner wall, whereby the stream directed through said conduit will be directed from one opposing wall to the other, each row of interceptors being composed of a plurality of blades.

6. The combination with a conduit having an inner annular wall, an outer annular wall forming an annular channel with said inner wall, a plurality of outer sleeves secured to the inner periphery of said outer wall, interceptor blades extending from said sleeves across the middle of said channel toward the inner wall and inclining in the direction of travel of the stream to be treated, a plurality 40 of inner sleeves secured to the outer periphery of said inner wall, interceptor blades extending from said inner sleeves toward said outer wall and inclining in the direction of travel of the stream to be treated, a discharge conduit in communication with the discharge 45 end of the annular channel formed between said inner and outer walls, and an intake member secured to said inner and outer walls at the inlet end of the channel formed between said walls, said intake member spacing the inner end of the inner wall from said outer wall and having a conical peak for deflecting the incoming air and fuel into the 50 channel formed between said walls.

JOHN WILLIAM SMITH.
